UNITED STATES PATENT OFFICE

134,051

DESIGN FOR A CULOTTE UNIFORM DRESS

Harry Moshontz, Cleveland, Ohio, assignor to H. Moshontz & Company, Cleveland, Ohio, a partnership composed of Harry Moshontz and Gilbert R. Schwartz

Application July 20, 1942, Serial No. 107,628

Term of patent 3½ years

To all whom it may concern:

Be it known that I, Harry Moshontz, a citizen of the United States and a resident of Cleveland, county of Cuyahoga and State of Ohio, have invented a new, original, and ornamental Design for a Culotte Uniform Dress, of which the following is a specification, reference being had to the accompanying drawing, forming a part thereof.

In said annexed drawing—
Fig. 1 is a front elevation of a culotte uniform dress, showing my design; and
Fig. 2 is a rear elevation thereof.

I claim:
The ornamental design for a culotte uniform dress, substantially as shown.

HARRY MOSHONTZ.
